CLAIM

The ornamental design for a vehicle, toy replica, and/or other replicas as shown and described.

DESCRIPTION

FIG. 1 is a front perspective view of a vehicle, toy replica, and/or other replicas according to the new design.

FIG. 2 is a front view thereof.

FIG. 3 is a rear view thereof.

FIG. 4 is a right-side view thereof.

FIG. 5 is a left-side view thereof.

FIG. 6 is a top view thereof.

FIG. 7 is a front left perspective view thereof.

FIG. 8 is a front right perspective view thereof.

FIG. 9 is a rear perspective view thereof.

FIG. 10 is a rear right perspective view thereof.

FIG. 11 is a rear left perspective view thereof.

FIG. 12 is a rear view thereof in a configuration without a spare wheel and tire installed.

FIG. 13 is a rear right perspective view thereof in a configuration without a spare wheel and tire installed.

FIG. 14 is a top view thereof in a configuration without a spare wheel and tire installed.

FIG. 15 is a rear perspective view thereof in a configuration without a spare wheel and tire installed; and,

FIG. 16 is a right view thereof in a configuration without a spare wheel and tire installed.

The portions of the vehicle, toy replica, and/or other replicas rendered in darker gray tones are claimed. The portions of the vehicle, toy replica, and/or other replicas rendered in a light gray tone form no part of the claimed design.
